CIGARETTE HOLDER AND BUTT EJECTOR

Antonio Di Rubbio, Brooklyn, N. Y.

Application March 12, 1943, Serial No. 478,937

2 Claims. (Cl. 131—182)

My invention relates to improvements in cigarette holders, the primary object in view being to provide a device of the character indicated equipped with a simple form of cigarette butt ejector which is easy to operate, dependable, will not easily wear out or get out of order, and is inexpensive to manufacture either as a separate part or as a unitary part of the holder.

Other and subordinate objects are also comprehended by my invention, all of which, together with the precise nature of my improvements, will be readily understood when the succeeding description and claims are read with reference to the drawing accompanying and forming part of this specification.

In said drawing:

Figure 1 is a view in side elevation of my improved cigarette holder,

Figure 2 is a view in longitudinal section, taken on the line 2—2 of Figure 1,

Figure 3 is a view in front end elevation,

Figure 4 is a view in rear end elevation,

Figure 5 is a view in transverse section, taken on the line 5—5 of Figure 1, and

Figure 6 is a view in longitudinal section of the ejector detached and drawn to an enlarged scale, the section being taken on the line 6—6 of Figure 2.

Referring to the drawing by numerals, my improved cigarette holder in the preferred illustrated embodiment thereof comprises a mouth bit 1 having an enlarged outer cylindrical end 2 and a reduced front end stem 3 formed with a flared terminal 4 ribbed, as at 5, to facilitate holding the stem in the mouth. The outer end 6 of the holder 1 has formed therein an axial socket 6 for the insertion therein of a butt end of a cigarette 7. Inner and outer annular slots 8, 9 are provided in the outer end of the holder 1 concentrically of the bore 6 for the reception of inner and outer, perforated, tubular guard shells 10, 11 for enclosing the cigarette 7 to protect the same and guard against fire hazard arising from flying sparks of the cigarette. The outer ends of the shells 10, 11 are connected together by an axial bolt 12, a nut 13, and a spacing collar 14, the bolt 12 extending through a cap piece 15. The shells 10, 11 and the parts 12, 13, 14 and 15 form no part of the present invention and need merely be identified in passing. Suffice it to further explain that said shells 10, 11 are detachable from the mouth bit 1 to permit insertion of a cigarette 7 in the socket 6 and when it is desired to eject a cigarette butt from said socket.

The butt ejector, with which my invention is 55

more particularly concerned, comprises a tubular ejector sleeve 16 and a sleeve-operating plunger rod 17 of tubular form and relatively longer than the ejector sleeve 16. The ejector sleeve 16 and the sleeve-operating plunger 17 may be formed of any suitable material. The ejector sleeve is endwise slidable in an axial bore 18 provided in the mouth bit 1 to extend inwardly from the socket 6 part way through said bit, said bore 18 being smaller in diameter than said socket for a purpose presently seen. The outer end of the ejector sleeve 16 is provided with an annular radial flange 19 slidably fitting in the socket 6 and, as will presently more clearly appear, designed to be thrust against the butt end of the cigarette 7. A longitudinally extending bayonet slot 20 is provided in the ejector sleeve 16, said slot having a pair of front and rear end notches 20', 21 extending laterally from opposite sides thereof, respectively. At the front end thereof the ejector sleeve 16 is provided with an internal annular flange 22 forming a restricted smoke draft opening 23 in the front end of said sleeve.

The sleeve-operating plunger 17 is endwise slideable and rotatable in a counterbore 24 in the mouth bit 1 extending axially from the inner end of the bore 18 to the terminal end of the stem 3 of said mouth bit and is slidably fitted in the ejector sleeve 16. The inner end of the sleeve-operating plunger 17 is provided thereon with a flanged, axially bored cap piece 26 suitably secured on said end to fit in a socket 25 in the mouth bit 1. The flange of the cap piece 26 is designed to abut the terminal 5 of the stem 3 of the mouth bit 1 to limit sliding movement of the sleeve-operating plunger 17 inwardly of said mouth bit, and provides a finger grip for use in manipulating said operating plunger. The sleeve-operating plunger 17 is of the proper length to extend into the ejector sleeve 16 past the outer end of the slot 20 when said operating plunger and said ejector sleeve are disposed in their limits of movement inwardly of the mouth bit 1. The limit of inward movement of the ejector sleeve 16 is established by a shoulder 27 formed in the mouth bit 1 by the juncture of the bore 18 with the counterbore 24. As best shown in Figures 2 and 6, in the inward limit of movement of the ejector sleeve 16 and said operating plunger 17, a lateral lug 28 on the outer end of the operating plunger is laterally aligned with the outer end notch 20' of the slot 20 and may be rotated into said notch to interlock the

ejector sleeve 16 and sleeve-operating plunger 17 against movement outwardly of the mouth bit 1.

The operation of the described butt ejector will be readily understood. In the described interlocked condition of the ejector sleeve 16 and the operating plunger 17, the flange 19 of said ejector sleeve is retracted into the socket 6 so that a cigarette 7 may be inserted in said socket. To eject the cigarette butt, the operating plunger 17 is rotated in the proper direction, through the medium of the cap 26 to move the lug 28 out of the outer end notch 20 into unlocking position. Said operating plunger may then be moved outwardly of the mouth bit 1 until said lug 28 abuts the other end of the slot 20, in which position thereof said operating plunger may be rotated in the proper direction to enter the lug 28 into the inner end notch 21 of the slot 20. In this position of the parts, the operating plunger 17 is interlocked with the ejector sleeve 16 in a manner such that under movement of said plunger inwardly of the mouth bit 1, the ejector sleeve 16 will be slid outwardly of said bit, and the socket 6 to eject the cigarette butt from said socket. The operating plunger 17 may then again be moved outwardly of the mouth bit 1 to retract the ejector sleeve 16 against the shoulder 27 and then rotated in the proper direction to retract the lug 28 from the inner end notch 21 of slot 19 so that said operating plunger may be then moved inwardly of the mouth bit 1 into its limit of inward movement and again interlocked with the ejector sleeve 16 by rotating the same to enter the lug 28 in the outer end notch 20 of the slot 20.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. A cigarette holder comprising a mouth bit having an outer cigarette holding end provided with an axial socket therein for the insertion of the butt end of a cigarette thereunto, a butt ejector sleeve endwise slidable in said bit in the axis thereof in opposite directions for projection outwardly of said socket and retraction into the bit inwardly of the socket, and means to advance and retract said sleeve, comprising a tubular plunger endwise slidable inwardly and outwardly of the other end of said bit in the axis thereof and including a flanged end abutting said other end of said bit to establish the limit of inward sliding movement of the plunger, said plunger being also rotatable in said bit, and coacting devices on said sleeve and plunger, respectively, for interlocking the plunger with opposite end portions of the sleeve under rotation of the plunger in opposite directions, respectively.

2. A cigarette holder comprising a mouth bit having an outer cigarette holding end provided with an axial socket therein for the insertion of the butt end of a cigarette thereunto, a butt ejector sleeve endwise slidable in said bit in the axis thereof in opposite directions for projection outwardly of said socket and retraction into the bit inwardly of the socket, and means to advance and retract said sleeve, comprising a tubular plunger endwise slidable inwardly and outwardly of the other end of said bit in the axis thereof and including a flanged end abutting said other end of said bit to establish the limit of inward sliding movement of the plunger, said plunger being also rotatable in said bit, and coacting devices on said sleeve and plunger, respectively, for interlocking the plunger with opposite end portions of the sleeve under rotation of the plunger in opposite directions, respectively, said devices comprising a longitudinal slot in said sleeve having a pair of oppositely extending lateral notches at opposite ends thereof, and a lateral lug on said plunger.

ANTONIO DI RUBBIO.
